UNITED STATES PATENT OFFICE

2,575,303

SWIMMING POOL

Joseph T. Sparling, Los Angeles, Calif.

Application July 8, 1947, Serial No. 759,494

2 Claims. (Cl. 1—172)

1

My invention relates to swimming pools and more particularly to that type which is adapted for installation wherever its use is desired. The primary object of my invention is the production of a swimming or bathing pool which is adapted to be pre-fabricated and easily assembled and installed at or in any location. To this end my invention employs a polygonal or suitably shaped tank structure made principally out of comparatively thin sheet metal and angle iron, reinforced in such manner as to produce maximum strength and rigidity so as to withstand various strains and prevent leaking. Flat side and end walls of a swimming pool body are subject to heavy lateral outward thrust by the weight of water in the body of the pool and when embedded in earth are subject to a counter inward thrust exerted by the ground, these tendencies being variable due to filling and emptying of the swimming pool. My improvement is adapted to fully overcome the effect of this thrust action and to provide a bathing or swimming tank or receptacle of reinforced structure which has maximum simplicity, permits of pre-fabrication, and requires a minimum of material and cost of construction.

Further objects and advantages of my improvement will be apparent from the following specification, of which the accompanying drawings form a part.

Fig. 1 is a plan of a swimming pool embodying my invention; Fig. 2 is a longitudinal side elevation; Fig. 3 is an end elevation looking at the right hand end of the structure shown in Fig. 1; Fig. 4 is an end elevation looking at the left hand end of the structure shown in Fig. 1; Fig. 5 is a plan of a detail at increased scale showing one corner of the tank or body structure; Fig. 6 is a section taken on the line 6—6 of Fig. 5; Fig. 7 is a section of a detail at increased scale, taken approximately on the line 7—7 of Fig. 2, and showing typical application of stiffeners for reinforcing the strength of the side and end walls; Fig. 8 is a section of a detail taken on the line 8—8 of Fig. 7; Fig. 9 is a section of a detail taken on the line 9—9 of Fig. 1, showing the drain connection from the trough; and Figs. 10 and 11 are respectively sections of details at increased scale taken on the line 10—10 and 11—11 of Fig. 1.

The body A of my improved swimming pool is advantageously made out of sheet metal which can be fabricated in parts and composed of a floor or bottom B, a pair of opposite side walls C—C and a pair of opposite end walls D—D. The side and end walls are substantially flat and upright as shown or they may be modified in shape and

2

inclined if desired. The floor or bottom B is constructed out of longitudinal series of flat plate sections or panels 10 which are butt welded together as at 11 (Fig. 11), by their contiguous and transverse edges and are arranged to form a gradual sloping portion 12, of wading depth at one end portion of the pool. Sections or panels 10 are also similarly welded together and form an abrupt double sloping portion 13—13, converging 10 downwardly and of diving depth in the adjacent portion of the pool. The general horizontal shape of the body is oblong or polygonal.

The opposite sides C—C as shown are of single piece form and have their lower edge portions 15 extended downwardly and shaped to closely meet and abut against the surfaces of sections 10, to which they are joined by welding at 14 as shown in Figs. 7 and 8.

The opposite pairs of side and end walls, C—C and D—D respectively are reinforced to withstand lateral thrust effort caused by the outward pressure of water in the body and inward pressure of earth when the body is imbedded in earth, by vertically disposed stiffeners 15. These stiffeners 25 are composed of longitudinal angle bars disposed vertically at suitable laterally spaced intervals apart. The stiffeners are secured by double welding the outer edges of one side of each bar at 16 to the contiguous outer surface of each side and end wall (Figs. 7 and 8).

The body of the swimming pool, when assembled and welded in the manner above described produces a rigid and substantial leak proof structure which is comparatively simple, durable and inexpensive.

A gutter E surrounds the upper edge portion of the body substantially horizontally and is intended to conform with any marginal shape thereof. This gutter is made out of horizontally disposed channel members 17, the horizontal webs (Fig. 6), of which form the bottom and the flanges 19 the sides. The inner flange of each channel section is welded along its longitudinal edges at 20 to the outer side and end surfaces of the body, while the upper contiguous abutting edges are substantially even horizontally as shown in Figs. 5 and 6. Adjacent end sections of the channel members are joined by miter joints 21 (Fig. 5), which are secured together by butt welding. In this manner any scum can be skimmed by overflow of water into the gutter. The mitered corner portions of the gutter are also supported by brackets 21'. A hand grip or grab rail F also surrounds above the upper edge of the body 55 A to aid bathers in entering or leaving the pool,

The hand grip is composed of sections 22 of pipe of suitable diameter (Figs. 5 and 6), joined by couplings 23 and supported above the gutter by the longitudinal angle bar sections 24. The contiguous ends of the angle bar sections are joined at the end corners of the gutter by welded miter joints 25, which correspond with the miter joints 21. The lower edges of the downwardly extending sides 26 of the angle bar sections 24 are secured to the floor 18 of the gutter by double welded joints 27 (Fig. 6). The gutter E is divided into inner scum and outer spit channels or troughs 28 and 29, by angle bar supporting members 24, the inner channel being adapted to receive scum by overflow from the pool and the outer channel 29 being adapted to receive any splash of water caused by bathers while bathing or holding the hand grip F. The angle bar supporting means for the hand grip forms a guard to isolate scum from physical contact for improved sanitary reasons.

A drain duct 30 is connected with the lowermost portion of the swimming pool. Also a drain duct 31 (Fig. 9) is connected through floor 18 of the gutter with both channels 28 and 29.

My improved swimming pool is adapted to be mounted upon any suitable support or to be imbedded solidly in earth with its upper marginal edge projecting above and substantially horizontal. When in use the circulating gutter around the upper marginal edge of the body confines and drains scum and splash water through separate channels which prevents contamination. The hand grip support which is shaped inwardly above the marginal upper edge of the body aids in protecting against contact with any scum which is removed from water in the pool. The channel members 17 in addition to forming the circulating gutter buttress and reinforce the side and end wall members C—C and D—D. These channel members coact with the stiffeners 15 in producing this effect whereby the walls of the body withstand all lateral thrust tendency exerted by the water in the pool and the inward thrust effort exerted by earth, in the event the body is imbedded in the ground.

In accordance with the patent statutes, I have described the principles of operation of my invention together with the construction thereof which I now consider to represent the best embodiment thereof, but I desire to have it understood that the structure shown is only illustrative and that the invention can be carried out by

other means and applied to uses other than those above set forth within the spirit of the invention and the scope of the following claims.

I claim:

- 5 1. A swimming pool structure having panel ends, sides and floor welded together to produce a liquid holding bathing receptacle, said floor being of panel construction and having an end portion of wading depth, and a downwardly converging portion of diving depth adjacent thereto, vertically disposed reinforcing stiffeners at horizontally spaced intervals apart secured to the external surfaces of said ends and sides, a drain duct connected with the converging lowermost portion of said floor, an endless drain gutter around the rim of said pool structure adapted to receive overflow from the pool, a hand rail above the gutter extended continuously around the pool structure, and an endless longitudinal support for the hand rail extended inwardly over said gutter and shielding the hand rail to prevent contamination by the overflow liquid in said gutter.
- 10 2. A swimming pool receptacle having a floor and reinforced enclosing walls, a drain gutter secured along the rim of said enclosing walls adapted to receive overflow from within said receptacle, a supporting wall dividing said gutter into an inner scum receiving channel and an outer splash receiving channel surrounding said enclosing walls, said supporting wall being extended inwardly above said scum receiving channel, and a hand rail on said inward extension over said scum receiving channel.
- 15 3. A swimming pool receptacle having a floor and reinforced enclosing walls, a drain gutter secured along the rim of said enclosing walls adapted to receive overflow from within said receptacle, a supporting wall dividing said gutter into an inner scum receiving channel and an outer splash receiving channel surrounding said enclosing walls, said supporting wall being extended inwardly above said scum receiving channel, and a hand rail on said inward extension over said scum receiving channel.
- 20 4. A swimming pool receptacle having a floor and reinforced enclosing walls, a drain gutter secured along the rim of said enclosing walls adapted to receive overflow from within said receptacle, a supporting wall dividing said gutter into an inner scum receiving channel and an outer splash receiving channel surrounding said enclosing walls, said supporting wall being extended inwardly above said scum receiving channel, and a hand rail on said inward extension over said scum receiving channel.
- 25 5. A swimming pool receptacle having a floor and reinforced enclosing walls, a drain gutter secured along the rim of said enclosing walls adapted to receive overflow from within said receptacle, a supporting wall dividing said gutter into an inner scum receiving channel and an outer splash receiving channel surrounding said enclosing walls, said supporting wall being extended inwardly above said scum receiving channel, and a hand rail on said inward extension over said scum receiving channel.
- 30 6. A swimming pool receptacle having a floor and reinforced enclosing walls, a drain gutter secured along the rim of said enclosing walls adapted to receive overflow from within said receptacle, a supporting wall dividing said gutter into an inner scum receiving channel and an outer splash receiving channel surrounding said enclosing walls, said supporting wall being extended inwardly above said scum receiving channel, and a hand rail on said inward extension over said scum receiving channel.
- 35 7. A swimming pool receptacle having a floor and reinforced enclosing walls, a drain gutter secured along the rim of said enclosing walls adapted to receive overflow from within said receptacle, a supporting wall dividing said gutter into an inner scum receiving channel and an outer splash receiving channel surrounding said enclosing walls, said supporting wall being extended inwardly above said scum receiving channel, and a hand rail on said inward extension over said scum receiving channel.
